US0D1024006S

(12) **United States Design Patent** (10) **Patent No.:** **US D1,024,006 S**
(45) **Date of Patent:** **** Apr. 23, 2024**

(54) **HEADSET**

(71) Applicant: **Logitech Europe S.A.**, Lausanne (CH)

(72) Inventors: **Chi Tat Chiu**, Hong Kong (HK); **Yi Hsun Liu**, Taipei (TW)

(73) Assignee: **Logitech Europe S.A.**, Lausanne (CH)

(**) Term: **15 Years**

(21) Appl. No.: **29/828,536**

(22) Filed: **Feb. 27, 2022**

(51) LOC (14) Cl. **14-01**

(52) U.S. Cl.

USPC **D14/205**

(57) **CLAIM**

The ornamental design for headset, as shown and described.

DESCRIPTION

FIG. 1 is a rear perspective view of the headset showing our new design;

FIG. 2 is a second rear perspective view thereof;

FIG. 3 is a front perspective view thereof with a boom microphone in an extended configuration;

FIG. 4 is a rear elevation view thereof;

FIG. 5 is a front elevation view thereof;

FIG. 6 is a top plan view thereof;

FIG. 7 is a bottom plan view thereof;

FIG. 8 is a left side elevation view thereof; and

FIG. 9 is a right side elevation view thereof.

FIG. 10 is a rear perspective view of a second embodiment of the headset showing our new design;

FIG. 11 is a second rear perspective view thereof;

FIG. 12 is a front perspective view thereof with a boom microphone in an extended configuration;

FIG. 13 is a rear elevation view thereof;

FIG. 14 is a front elevation view thereof;

FIG. 15 is a top plan view thereof;

FIG. 16 is a bottom plan view thereof;

FIG. 17 is a left side elevation view thereof; and,

FIG. 18 is a right side elevation view thereof.

The broken lines shown in the figures form no part of the claimed design.

1 Claim, 14 Drawing Sheets
